HEATING APPLIANCE WITH TIMER

Reproduced as

Raymond D. Smith, Pleasantville, N. Y.

Application February 17, 1928, Serial No. 255,000 corrected

4 Claims. (Cl. 161—16)

This invention relates to heating appliances having timing mechanism incorporated therewith for automatically governing the current supply to the appliance, or for other purposes.

5 The invention aims to provide an improved form and an improved disposition of the timing mechanism as to its structural association with typical types of appliances, such as toasters, percolators, waffle irons, chafing dishes, and the like 10 now in general use in the home and in restaurants, hotels, etc.

Another object is to provide timing mechanism for this purpose which shall have an operating handle disposed for more convenient manipulation and more easily selected accuracy of setting to predetermine a time interval.

Another object is to provide a control switch for the appliance arranged to be operated directly by the time setting handle and independently, if desired, of the timing mechanism.

A particular object is to avail of the usually wasted space comprised by the base of the smaller types of domestic heating appliances exemplified by the ordinary table toaster herein employed to 25 illustrate the principles of my invention, and to locate my improved timing mechanism within the confines of such base with the following advantages. For increase of stability of the relatively light appliance as compared with the practice 30 heretofore of incorporating timing mechanism within the structure of such appliances but above the base. For the universal adaptation of a single type of timing mechanism to the many and variegated designs of heating appliances 35 whose structural similarity is limited to the common possession of such a base. For the consequential small amount of change and expense of production involved in applying my improved timing mechanism to different types of existing 40 appliances. For the ability to retain the original size, proportions and decorative design of existing appliances to which the qualities cited are of great commercial importance. For the easy converting of an ordinary, non-automatic 45 heating appliance into an automatic time controlled appliance by the mere application to same of my improved timing mechanism according to the principles herein disclosed and claimed.

50 A still further and particular object is to so mount the timing mechanism that the noise of the running of its movement shall be deadened as much as possible and the transmission of this noise or of the vibrations which cause the same 55 to any parts of the appliance which might act

to amplify the same be prevented or minimized. Other objects will appear hereafter.

In the drawing, Fig. 1 is a side view of an ordinary table toaster showing an example of the improved application of timing mechanism thereto.

Fig. 2 is an end view looking from the right at Fig. 1.

Fig. 3 is a plan view of the base of the toaster taken in section on the plane 3—3 in Figs. 1 and 10 2 looking downwardly.

Fig. 4 is a wiring diagram of the electrical connections.

Fig. 5 is an isometric view of my improved timing mechanism and the electric switch together with the means for silent mounting of same removed from the base of the toaster.

Fig. 6 is an enlarged fragmentary view of the toaster base seen as in Fig. 2 with the addition of a time setting adjustable stop.

Fig. 7 is a fragmentary view in section on the plane 1—1 in Fig. 6 looking in the direction of the arrows.

Fig. 8 is a plan view of the time limit switch unit of Fig. 5 but showing a switch and back-set mechanism employed of the type disclosed in my co-pending application Serial No. 183,838, Patent No. 1,984,204 of December 11, 1934.

Fig. 9 is an edge view looking from the right at Fig. 8.

Fig. 10 is a view of the back-set mechanism of Fig. 9 taken in vertical section on the plane 10—10 of Fig. 8.

Fig. 11 shows the parts which engage whereby the turning of pinions exterior of the movement 35 plates is caused to operate the switch.

Fig. 12 is a rear view taken on the vertical plane 12—12 in Fig. 10 looking in the direction of the arrows and showing details of the back-setting clutch and stop parts associated therewith.

Fig. 13 is a view similar to Fig. 12 on an enlarged scale showing certain of the parts broken away to reveal the flip stop whereby the power spring of the movement is wound, certain parts 45 being sectioned on the plane 13—13 in Fig. 10.

In Figs. 1, 2 and 3 the superstructure of the toaster which I have chosen to show merely as illustrative of a superstructure common to a great variety of heating appliances, may comprise the heating element 10 carried by and insulated from a frame structure 11 having a top 12 and mounted at its bottom on the base 13 and carrying, arranged for suitable access and movement for subjecting the bread to be toasted to 55

the heat of element 10, the carriers 14, the details of which are immaterial to the scope of the present invention.

As is almost universal in the construction of 5 toasters and other heating appliances the base 13 is hollow and in the particular example here pictured comprises an inverted tray supported in slightly elevated position by four leg pieces 15.

Within this hollow of the base I may mount 10 in any convenient way a timing mechanism comprised between the movement plates 16 and 17, the mounting means for which in the present example of construction comprise two longitudinal strips 18 which may to good effect be made 15 of thin tempered steel to give them a resilient quality less disposed to transmit the vibration of sound from the movement to the base 13 and as added precaution against such transmission of sound, I may space strips 18 from the base 13 by 20 washers 19 of felt or other sound absorptive material at their extremities where they are fastened to the base. I may introduce similar washers 20 to separate strips 18 from the lateral bars 21 where attached thereto and which bars are fixedly 25 secured to the movement plate 16. Strips 18 may be given an S-shaped or other non-straight configuration to increase their effective length.

Movement plates 16 and 17 are rigidly spaced and connected by posts 22, two of which at the 30 left end of the movement may carry secured thereto the electric snap switch 23 having the stationary contacts 41-41 and the movable contacts 42-42 to be operated by the timing mechanism, which as before stated occupies the space 35 between plates 16 and 17 or between corresponding plates 114-113 of Figs. 8 to 13, inclusive. In the particular form of timing mechanism here illustrated, the exact nature of which, however, may be varied at will within the scope of this 40 invention, the external pinion 24 serves as the sole means of operating not only the timing mechanism but also the switch 23 and is itself operated by a segment 25 carried on the lever 26 pivoted at 27 and having the handle 28 at its end. 45 The spring 29 may act upon lever 26 to urge it into its normal position indicated by full lines in Fig. 5. The use of this spring would not be necessary if the time giving mechanism carried by the plates 16 and 17 is to comprise in itself a 50 complete spring motor motivated by some conventional form of power spring such as that indicated at 131 in Fig. 9, but in a more simple form of time movement any additional power spring equivalent to 131 might be eliminated in which 55 case throwing lever 26 from its full line position to its broken line position in Fig. 5 will rotate the pinion 24 as permitted by one way slippage of any conventional form of winding ratchet which after permitting this winding movement of 60 pinion 24 will permit its reverse movement under the impulse of spring 29 only so fast as the running of a retarding train may permit. Mechanical connection between the timing movement and the switch 23 operated thereby may be such that 65 in the full line position of lever 26 the switch will be open and the current received from the attachment cord 38 by prongs 31 will be cut off from circuit through the heating unit 10, and that when lever 26 is slightly displaced from its 70 full line position the consequent movement of pinion 24 will act to close the switch and supply current to element 10 until such time as the reverse action of pinion 24 under the power of spring 29 shall return lever 26 to its full line posi-

tion and automatically open switch 23 cutting off the current to element 10 to prevent the toast from burning.

I may mention that the construction of prongs 31 may be conventional and of fully standardized 5 commercial form and that the connection from one of these prongs direct to the left end of heating element 10 is by means of wire 32 and that the connection from the other of said prongs to the opposite end of heating element 10 is through 10 wire 33 leading to binding post 34 of switch 23 and through wire 35 from the binding post 36 of switch 23 to the right hand end of the heating element 10 (see diagram of connections in Fig. 4) and all electrically alive parts are, of course, thoroughly insulated from the metallic portions of the toaster structure and timing mechanism.

Particular attention is called to a stationary abutment or rest 37 at the left end of slot 38 in base 13 for lever 26 and to a corresponding abutment or rest 39 near the right end of said slot. Both of these abutments are preferably somewhat lower than the center of lever 26 as only one of them is used at a time and its purpose is, in the case of abutment 37, for resting the thumb 43 against same while the index or second finger 44 of the operator's same hand grasps the handle 28 for pulling it to the left in Figs. 2 and 3, after which if it be desired to move the lever 26 in the opposite direction the thumb is placed against 30 handle 28 and some finger of the operator's same hand grasps the rest 39 as a corresponding means of moving handle 28 a definite desired amount to the right in Figs. 2 and 3. I do not, of course, limit my invention to this precise manner of 35 manipulating handle 28 and may eliminate one or both of abutments 37 and 39, the sides of the toaster being graspable for the purpose of rests 37 and 39 if same are absent, but they are extremely useful and I believe the idea is novel in 40 this art for the convenient and accurate accomplishment of a desired time setting of a handle such as 28 to register with graduations 40 which may be marked on the base 13.

This disposition of a time setting lever to 45 protrude from the wall of a utensil in such relation to adjacent corners of the utensil contour or as a substitute for same the finger rests 37 and 39 respectively useable to assist in the control of pulling the handle 28 just the desired distance in 50 both directions, is of particular use when I employ for operation by means of a lever in a utensil a time limit switch unit incorporating the back-set principle disclosed in several of my co-pending 55 applications illustrative of which I have copied in Figs. 8 to 13 inclusive certain parts of the structure disclosed in my co-pending application Serial No. 183,838 and in said figures show same equipped with the same operating lever 26, gear segment 25 and pinion 24. It will not be necessary to 60 describe the details of this optional form of time limit switch beyond making clear an example of mechanism which affords the back-set feature, meaning the ability, after any original displacement of lever 26 for closing the switch and at the 65 same time winding and starting the time movement, of manually returning lever 26 any desired amount of its displacement from its starting position thereby to reduce or to cancel the effective 70 time setting initially given, or to manually turn the switch "on" and "off" if desired as though the time mechanism were not present.

In Figs. 8 to 13 inclusive I show a simpler form of snap switch 100 the details of which will not be described other than to explain that rocking 75

movements of the operating fork 101 at any speed snaps the movable contact 102 to and from its broken line position in Fig. 8 where it conductively bridges the contact bracket 103 and the contact bracket 104 carrying the screws 105 for connection to the circuit wires. Brackets 103 and 104 are secured in insulated relation on the body 106 of the switch, itself composed of insulating material and mounted by means of cap or frame portion 107 carrying the pivot pin 108 for the switch fork 101. In Fig. 16 this fork is seen to be formed with an offset for engagement by the cam finger 109 secured on the periphery of cam 110 by the screw 111.

15 The cam 110 is loosely rotatable on the shaft 112 pivoted at its rear end in the frame plate 113 and at its forward end in the frame plate 114, which shaft carries pinned to its forward or upper end the pinion 24 and is retained at its rear end 20 by the screw 115.

25 Shaft 112 is slabbed or flattened for some distance from its end engaged by screw 115 and engaging this flattened portion so as to turn fixedly with the shaft is the trip 116, a forwardly extending tongue 30 117 on which, engages an opening 118 in the cam for propelling the latter in both directions of rotation but with a small amount of play or lost motion owing to the opening 118 being wider than the tongue 117. The trip 116 further has a rearward bent tongue or terminal 119 in the path of which a swinging stop member 120 is swivelled on a bushing 121 carried by the pivot pin 108 at the side of the switch cap and positively backed up by tongues 122 and 123 which may be struck from 35 the frame plate 113. Thus while the stop member 120 precludes more than a complete turn of the trip 116, it affords the full extent of a complete turn because of its limited ability to swivel between tongues 122 and 123 as described. The extra space between trip 116 and the frame plate 40 113 is taken up by a spacer collar 124. The shaft 112 further carries a radially projecting pin 125.

45 From reference to Figs. 10, 12, and 13 the pin 125, or the projecting portion thereof, is seen to ride freely in an annular recess 126 in the gear 127 except for its engagement at one point with the L-shaped flipstop 128 pivoted in the wall of gear 127, extending into the recess 126 and limited in its shifting movement by abutment against 50 opposite corners of an outward extension of the recess 126. As with the case of the stop member 120 this limited swing movement of flipstop 128 permits a full relative circle of movement of shaft 112 relative to gear 127 but precludes any substantially greater amount of relative movement.

55 The gear 127 is in mesh with a winding gear 129 given bearing between the frame plates 113 and 114 and fixed to rotate positively with the winding spindle 130 of an ordinary time movement which may be disposed in any positional relation to the frame plates 113, 114 to fall therebetween or exterior thereof as here shown, the band spring 131 connecting the spindle 130 to some frame post in the usual manner, and the usual parts of a retarding train being in part indicated without detailed description.

60 After any winding of the spring 131 by turning of the spindle 130 in a contra-clockwise direction in Fig. 8 the power of this spring governed by the retarding train slowly rotates spindle 130 in the reverse or clockwise direction in Fig. 8 and thereby rotates the gear 127. The flipstop 128 will pick up and engage the shaft pin 125 whereby the shaft and the trip 116 will be rotated contra-clockwise in Fig. 8 or clockwise in

Figs. 12 and 13 until stopped by the member 120 in the position shown in Fig. 12 corresponding to which the cam finger 109 is positioned as in full lines in Fig. 11 and the switch is positioned to break the circuit. Conversely if the lever 26 be moved from its full line position in Fig. 8 toward its broken line position, segment 25 will impel pinion 24 in a clockwise direction. Pin 125 will engage flipstop 128 and thereby impel gear 127 in corresponding direction and gear 129 will be rotated to again wind the spring 131 for another cycle of timing action.

65 From the foregoing description it will be plain that whereas all of these rotating parts are strictly limited to a stop determined normal or zero position corresponding always to a given state of unwinding of the spring 131, all of these parts except the two gears 127 and 129 are free for manual return to this normal zero or starting position (see Figs. 11 and 12) at any time and without waiting for the corresponding return of gear 127, which will be effected only by running of the time movement, because the shaft pin 125 acts only as a pusher with respect to the flipstop 128 and can recede from same at any time for return to its starting position. This much of the construction alone would give the ability to throw the switch off manually without waiting for the set time to elapse but it may sometimes be desired that in addition to this ability of cancelling the effective time setting there shall be provided a means of reducing the effective time setting and yet leave the timing mechanism with some smaller period to run before it shall act to break the circuit. This may be accomplished by a slippable 30 ratchet clutch consisting of the ratchet wheel 132 secured fixedly to the side of gear 127 and engaged by a pawl 133 pivoted to the cam 110 by the stud 134 and urged by the spring 135 into engagement with the teeth of ratchet wheel 35 132. An ear 136 falls closely adjacent to a tripping projection 137 on the trip 116 so that the slight relative movement of trip 116 relative to cam 110 is sufficient to lift the pawl 133 free of the ratchet wheel 132 for adjustment of cam 110 40 to different rotative positions with respect to gear 127 so that pawl 133 may seat itself in any desired tooth of the ratchet wheel 132 to be clutched and impelled thereby in the absence of flipstop 128 and shaft pin 125 being in engagement. It will be noted, however, that if the trip 116 is impelled back to its normal or starting position by means of this ratchet clutch mechanism, and there stopped by the member 120, the running down of spring 131 does not 45 cease until the flipstop 128 has caught up with and becomes obstructed in its running by the shaft pin 125, because when the rotative travel of trip 116 is prevented by the stop member 120, each tooth of ratchet wheel 132 is enabled to 50 escape and pass the engaging pawl 133 owing to the lost motion relation of the cam 110 to the trip 116 and the consequent tripping or releasing action of pawl 133 which otherwise would constitute a positively impelling clutch so long 55 as trip 116 is unimpeded in its travel. For instance, were the cam 110 to be stopped instead of the trip 116, ratchet wheel 132 could not continue to pass the pawl 133 and the running of all parts and the running down of the spring 60 135 would immediately be checked.

65 It will thus be clear that in connection with the lever 26 when equipped to operate a back-settable time limit switch such as that illustrated in Figs. 8 to 13 inclusive, the disposition of han- 70 75

dle 28 so that same may be grasped simultaneously with the remote side of the toaster base, or in fact either side of the toaster base whatever its position, is a material factor in the convenience of manipulation, for many appliances are so light when designed to be portable, as is the case with most modern table appliances, that otherwise in order to operate a time limit switch by a horizontal lever, the appliance would have to be held down by one hand while the lever was moved by the other hand of the operator, requiring the employment of two hands, whereas the timer of these improvements not only has the space saving merit of being horizontally disposed, but so disposed, can be operated in its entirety either as a plain switch—"on" and switch—"off" device or as an automatic time limit cut-off by the operator's either hand alone.

From the foregoing description and from a comparison of Fig. 3 with Fig. 8, it will be noted that as an incident to the direction of rotation of parts, the scale of time graduations as shown in Fig. 3 would need to be reversed to place the normal or zero point end of such scale at the left instead of at the right end of slot 38 for accord with the timer mechanism of Figs. 8 to 13 because in plan view and looking downward the operating lever 26 as shown in zero or normal position by full lines is at the end of its swing opposite to the functionally corresponding position of this same lever as shown in full lines in Fig. 8. This will serve to illustrate the interchangeability of the directions in which the operating lever may be constructed to move and still partake of the benefits of the features comprising the present improvements.

In connection with the foregoing description I believe that there are many points of novelty in the herein disclosed arrangement of timing mechanism which do not depend upon the location of same in the base of the toaster but which would be equally advantageous in any arrangement of timing mechanism associated with the superstructure of the toaster above the base and the claims hereto appended will not, therefore, be understood to limit the location of the timing mechanism to any particular portion of the structure of a toaster except where same is explicitly stated.

In Figs. 6 and 7 for purposes of making it possible to repeatedly set the timer for the same duration of run and by the sense of feel, if desired, rather than by reference to the graduations 40, I may provide any adjustable means stationable at selected positions in the path of lever 26 or handle 28 to act as a stop for same. One of many such devices that may be employed is shown in Figs. 6 and 7 the particular illustrative construction comprising a bolt having the head 45 and integral therewith the rectangular shank 46 extending through and freely fitting the slot 47 in the toaster base 13 below the lever slot 38, although the last mentioned slot could as well be used for this purpose. The stop 48 having the hub 49 has a corresponding rectangular hole fitting the shank 46 and kept from turning thereby and by the engagement of shank 46 with slot 47 but freely slideable on said shank so that tightening the thumb nut 50 clamps the head 45 against the inner surface of the side of base 13 and the stop 48 against the outer surface providing convenient means to vary the position of stop 48 and secure it in place. In these figures also is better shown a pointer 51 which may depend from lever 26 to register with graduations 40 when same are employed.

The attachment prongs 31 may be located elsewhere on the toaster. The handle 28 may be mounted to protrude from other sides or portions of the toaster, structure or other heating appliance, in some of which appliances such as percolators or waffle irons, the base, while commonly shallow, may be in plan view of other geometrical shapes than square or rectangular, such as round, octagonal, etc. Also the slot 38 or its equivalent may be formed in the top or horizontal portion of base 13 and the handle 28 up-turned to protrude, such slot in that case made curved if handle 28 is to swing with lever 26, but such handle may be given gear and rack connection to lever 26 instead of travelling fixedly therewith, or may be carried by a rack meshed directly with pinion 24 in which arrangement the path of travel of handle 28 would be straight instead of curved. I may also operate pinion 24 by a worm gear, or bevel gear connection, or the equivalent, eventuating in a dial, knob, or handle the equivalent of handle 64 in my co-pending application Serial No. 183,838 filed April 14, 1927, and protruding from any part of the appliance or its base. The circuit connections and the exact type of switch employed may be varied at will as may also the location of the switch in the toaster. Where a switch is omitted and the function of the timing mechanism is, instead of or in conjunction with a switching operation, to move the food or material being treated or in any way vary its effective relation to the heat in the appliance, it will be appreciated that my novel arrangement and disposition of timer is equally advantageous.

I do not consider it new in this art broadly to combine a timing mechanism with a heating element within the structure of a toaster but I do believe it to be novel and of great practical advantage to locate and construct a timing mechanism in a way characterized by the several features hereinbefore described and particularly pointed out in the appended claims.

I claim:

1. In combination with a timing mechanism, a handle for operating same pivoted for limited swinging travel, a rest positioned near one end of said travel and sufficiently close to the other end of said travel to permit the simultaneous grasping of said rest and said handle by the thumb and a finger of one hand in all positions of said handle, said rest being outside the plane of movement of said handle to expose the latter for easy grasping when displacing said handle from proximity to said rest.

2. In combination, a timing mechanism carried between two spaced and rigidly connected bearing plates, a support on which said mechanism is mounted, and means for mounting said mechanism on said support including fastening projections overlying the edges of said plate and mounting strips extending from said projections to said supports and separated from direct contact with both by relatively yielding means.

3. In an automatic appliance, a timing device connected to control the action of said appliance and housed therewithin, a time setting lever, a wall of said appliance having an opening through which said lever protrudes, graduations to represent intervals of time arranged lengthwise of said opening, connections between said lever and said timing device whereby displacement of said lever from a limit position winds the power spring of the timing device a proportional amount indicated by said graduations, said connections acting to impel said lever slowly back to its limit po-

sition as the power spring plays out, and auxiliary connections between said lever and said timing device causing said lever to be so impelled to its limit position within a space of time proportional to its displacement from said position irrespective of the extent of winding of said power spring.

4. In combination with the hollow base of a table appliance shaped to afford a shallow compartment having a top horizontal wall, a combined electric snap switch and cooperative time control movement assembled to comprise a structural unit to be housed within said compartment, and including a train of time wheels, spaced metallic plates pivotally supporting the wheels therebetween, electric circuit terminals, an insulative switch body carrying said terminals and deriving support from one of said plates and lo-

cated on the same side thereof as is the other plate for compacting the overall thickness of the combined switch and movement unit to a minimum dimension, a handle pivoted to swing for operating said movement, a switch member insulated from said handle and movable to make and break circuit through said terminals, and spring toggle mechanism enabling said handle to propel said switch member with a lagging snap action in both directions, together with means to mount the said unit as an integral structure upon the lower surface of said wall in a manner to be accessible from the bottom of the appliance without removal of the unit from the said compartment.
